UNITED STATES PATENT OFFICE.

GEORGE L. ESTES, OF OKLAHOMA CITY, OKLAHOMA, ASSIGNOR TO EZRA L. ESTES,
OF SHAWNEE, OKLAHOMA.

DEPRESSIBLE TRAFFIC SIGNAL.

Application filed June 7, 1926. Serial No. 114,208.

The present invention relates to traffic signal devices, and aims to provide a novel and efficient warning signal for intersecting trafficways and of such a character as not to offer any obstruction to the traffic vehicles.

Accordingly, the principal object of the invention is to provide a signal device designed to be mounted upon the surface of a highway and having a movable signal member adapted to be depressed by engagement with the wheels of the vehicles, and thereafter return automatically to upright or signaling position.

With these general objects in view, the invention will now be described by reference to the accompanying drawing illustrating one form of construction which I have devised for carrying out the foregoing objects of the invention, after which those particular features and combinations deemed to be novel will be particularly set forth and claimed.

In the drawing—

Figure 1 is a front elevation, illustrating a signal device constructed in accordance with the present invention;

Figure 2 is a vertical section, representing a section taken on the line II—II of Figure 1;

Figure 3 is a plan view of the device;

Figure 4 is a central vertical section, representing a section taken on the line IV—IV of Figure 3;

Figure 5 is a transverse section taken on the line V—V of Figure 4; and

Figure 6 is a detail section, taken on the line VI—VI of Figure 1.

Referring now to the drawing in detail, this shows my improved signal device as comprising a base plate member 10 which is adapted to be mounted upon the surface of a highway, indicated at 12, and anchored thereto by means of any suitable fastening means 14, such as screws, bolts, pins or the like. Mounted centrally and longitudinally of the plate 10 is a bearing bracket member 15 removably secured to the base plate by like screws 16. The bracket member is formed with bearings 17 for journaling a shaft 18 designed to afford an oscillating support for the signal member proper comprising the plate 19, the lower corners of which are formed with projecting lugs 20 for embracing the shaft 18 adjacent to the bearings 17. One of said lugs 20 embraces

the squared portion 18' of said shaft, which portion 18' also carries a crank arm 22 having a forked end 23 and pin 24 for attaching a rod 21 carrying a series of weight elements 25. These weight elements are suspended within a housing 26 formed at one end of the base plate 10 and adapted to be embedded substantially entirely below the surface of the highway. To prevent too great a range of movement of the weights, the latter are yieldingly connected by means of spring elements 27 to the sides of the housing 26 (Figure 2). A cap member 28 is removably secured by means of screws 29 to the top margin of the housing 26.

At least one of the faces of the signal member 19 is designed to carry the desired signal indicia such as the letters forming the word "stop", or whatever other warning, such as the word "slow", or the like, that is to be given to approaching traffic. Preferably also the signal member is provided with suitable reflector elements such as disks of colored glass 30, adapted to be illuminated by the glare of headlights; these are secured in pairs to the opposite faces of the plate 19 by means of disk holder plates 32 and a single bolt 34 for each pair of said disks 30 and plates 32, as shown in Figure 6.

In practice, it is proposed to mount the above described device at either the margin, that is, side edge portion of a highway, or at any appropriate point, such as the middle of the street or trafficway where it merges into a cross or intersecting highway. In either case, the weight housing portion 26 is embedded below the surface of the pavement or road bed, leaving the base plate 10 resting flat on the top surface of the pavement or roadbed where it and the movable signal member may be engaged by the wheels of the traffic, if need be, without offering any material obstruction to the latter. Thus, when the traffic is obliged to pass directly over the signal member, this being free to rock with the shaft 18, simply swings in either direction, as indicated in Figure 2, and thereafter is automatically restored to upright position by the action of the weights 25. Likewise, when the device is engaged by street cleaning, street sweeping or other devices, their operation is not interfered with by my signal device, and no damage is done to the latter. The height of the bearing member 15 represents the total amount of 110

the projection above the surface of the pavement or roadbed as the signal member is depressed, so that the obstruction to traffic moving in either direction is practically a negligible quantity. Any desired indicia may be placed upon the other face of the signal member, such as the name of the cross highway in case the signal is mounted at a highway intersection. The demountable character of the signal and the bracket members enables these and the cap member 28 to be removed in the winter season in some localities, if desired, on account of ice, etc., obstructing its operation, the housing 26 being simply filled up temporarily with earth or gravel to present an even top surface.

It will thus be seen that I have provided a practical and inexpensive device for carrying out the desired objects of the invention, and while I have illustrated what is now regarded as its preferred form, I desire to reserve the right to make such changes as may fairly fall within the scope of the appended claims.

What I claim is:

1. A traffic signal device comprising a base plate adapted to be supported directly upon the surface of the road bed, and provided with a housing projecting below the plane of said base plate, an oscillating shaft mounted on said base plate and provided with a crank arm carrying a weight suspended within said housing, and a signal member carried by said shaft and normally maintained by said weight in upright position.

2. A traffic signal device comprising a base plate adapted to be supported directly upon the surface of the roadbed, and provided with a housing projecting below the plane of said base plate, an oscillating shaft mounted on said base plate and provided with a crank arm, a weight pivotally and freely suspended from said crank arm, yielding means associated with said weight and restraining the latter from excessive swinging movement, and a signal member carried by said shaft and normally maintained by said weight in upright position.

In witness whereof I hereunto affix my signature.

GEORGE L. ESTES.
